UNITED STATES PATENT OFFICE.

JOHN SCHUMACHER, OF LOS ANGELES, CALIFORNIA.

METHOD AND APPARATUS FOR FORMING PLASTER BOARD.

Application filed February 24, 1925. Serial No. 11,169.

To all whom it may concern:

Be it known that I, JOHN SCHUMACHER, a citizen of the United States, residing at Los Angeles, in the county of Los Angeles and 5 State of California, have invented a new and useful Method and Apparatus for Forming Plaster Board.

This invention relates to a method and apparatus for forming plaster board. 10 With the method and apparatus for forming plaster board heretofore employed the edges of the plaster board as formed are rough and uneven and hence it is necessary to cut away a portion of the board and trim 15 the same to form a finished product. This involves considerable expense and waste of materials.

It is an object of the present invention to provide a method and apparatus for forming 20 plaster board, which is adapted to form a finished edge upon the plaster board as the board is formed to the end that the ordinary expense of cutting away and trimming the edges of the plaster board as 25 formed may be eliminated and that a decreased waste be obtained in the formation of the plaster board.

Various other objects and advantages of 30 the present invention will be apparent from a description of a preferred form of the method and apparatus for forming plaster board embodying the invention. For this purpose reference is made to the accompanying drawings illustrating a preferred form, 35 or example, of an apparatus for forming plaster board embodying the invention and by the use of which a preferred method of forming plaster board may be practiced.

In the drawings:

Fig. 1 is a side elevation partially in vertical section of the apparatus.

Fig. 2 is a plan view, part of the feeding and trimming apparatus being removed.

Fig. 3 is an enlarged front elevation of the spreading and forming means.

Fig. 4 is a section on the line 4—4 of Fig. 3.

Fig. 5 is a fragmentary elevation, partially in vertical section of certain parts of 40 the forming and spreading means, and

Fig. 6 is a section on the line 6—6 of Fig. 5.

Referring to the drawings, the apparatus there illustrated comprises a hopper 2 for holding and supplying plastic or cementiti-

ous material which is to be incorporated in the plaster board. 3 indicates a mixer for mixing the plastic or cementitious material with water supplied from a pipe 4, the mixer 3 preferably consisting of a trough 60 in which are mounted rotatable mixing blades 5, the blades being mounted upon a shaft 6 driven by a pulley 7. 8 and 9, respectively, indicate supply rolls of fibrous covering material which furnish the covering sheets for the plaster board to be produced. 10 indicates a sheet or strip of fibrous material supplied from the roll 8 for forming the lower covering sheet of the produced plaster board, whereas 11 indicates 70 a sheet or strip supplied from the roll 9 as the upper sheet of the plaster board forms.

The sheets 10 and 11 are indicated as passing to the plaster board forming spreading means generally indicated at 12. 75 Suitable advancing means 13 are provided for continually conveying the plaster board being formed to the discharge end of the apparatus, such advancing means being indicated as comprising a conveyor 16. The advancing means 13 is adapted to discharge successively separate portions of the formed plaster board upon a receptacle such as a truck (not shown).

The spreading and forming means 12 of the apparatus include an upper roller 20 and a lower roller 21, spaced apart to determine the thickness of the finished board. As the sheets 10 and 11 are fed between the rollers 20 and 21, plastic or cementitious material is fed from the hopper 2 onto a box 17 likewise positioned on the advancing means 13 from which the plastic or cementitious material is spread by the rollers 20 and 21 and with the sheets 10 and 11 formed to a proper thickness of plastic board. In so far as the apparatus and method of forming plaster board has been particularly described, it is similar to the present generally accepted apparatus and method particularly described and claimed in Patent No. 1,176,322, granted to John Schumacher and Joseph E. Schumacher, March 21, 1916.

With the ordinary type of such plaster board method and apparatus the edges of the board as they leave the forming and spreading means 12 are irregular and the unequal edges must be cut off and the board trimmed with a corresponding waste of material and increased production cost. By 110

the method and apparatus of this invention, these disadvantages are overcome.

- In accordance with the principles of this invention, the sheets of fibrous covering material 10 and 11 fed to the spreading and forming means are made substantially equal length to the rolls 20 and 21 of the spreading and forming means. This, of course, may be accomplished by the use of rolls 8 or 9 of the fibrous covered material substantially corresponding in width with that of the rolls 20 and 21. In order to insure the sheets supplied to the spreading and forming means 12 being of the proper thickness 10 to correspond with such rolls, however, it is generally preferable to provide a trimming means for the sheets positioned in advance of the rolls 20 and 21. 22 and 23, respectively, generally indicate suitable trimming means for the respective sheets 10 and 11. These trimming means may be of any desired or preferred form such as disc knives 24 and 25, respectively, and may be driven in any desired manner.
- 25 Where mention is made of the provision of the feeding or trimming of sheets 10 and 11 to correspond with the width of rolls 20 and 21 of the spreading and forming means, it is understood that the sheets 10 and 11 are 30 made to be of equal length with the rolls 20 and 21, as they pass therebetween. Inasmuch as the contact with the moist plastic or cementitious material supplied from box 17 causes in operation a slight swelling of 35 the sheets 10 and 11 amounting to a fraction of an inch the trimming of the sheets by the devices 22 and 23 are governed accordingly. This makes the sheets 10 and 11 as cut by the trimming means slightly narrower than the 40 width of the rolls 20 and 21.
- In carrying out the objects of the invention a method and apparatus is provided for continually smoothing the edges of the plaster board as formed in order that a smooth clean 45 edge will be obtained. Hence trowels 26 are provided at each end of the rolls 20 and 21. The trowels 26 may be of various constructions and operated at different manners, the essential feature of the invention being the 50 provision of a driven or moving trowel 26 for continually trowelling or smoothing the edges of the plaster board as it is formed. The term "trowelling" is employed herein to indicate the operation of smoothing and 55 forming the edge of the plasterboard by a motion of a forming tool, such as the trowels 26, relatively transverse to the plasterboard as formed, so that the board, while being formed, is not only provided with a wall to 60 limit the outward motion of the plaster, but such wall is given a smoothing and edge-forming motion relative to the plasterboard to produce the desired finished edge. The 65 members 26 are trowels, since during each rotation such members pass once downwardly

transverse to the formed board and then upwardly transverse to the formed board, thus rounding the corners of the board and forming a smooth edge. In the specific form of the invention the trowels 26 are illustrated 70 as discs mounted flush against the ends of the upper roller 20 and extending as a flange therefrom down against the edges of the lower roll 21 where the plaster board is formed. Such trowels, of course, could be 75 attached to the roll 20 in various manners. However, for reasons hereafter apparent they are preferably affixed thereto in the following manner.

An annular trowel supporting body 27 is mounted on the end of the shaft or axle 28 of the roll 20. This body is then bolted or otherwise secured to the rolls 20 as indicated at 29. The body 27 is provided with an annular recess 30 for the reception of the inner end of the disc trowel 26 and the trowel is then held thereto by bolts or pins 31. The trowel supporting body 27 is cylindrical in form and serves to mount a trowel cleanser 32, which is preferably fixed 80 against rotary motion and held on the body 27 by a plate 33 secured by means 34 to the body 27. The cleaning member 32 is recessed as indicated at 35 to fit the disc trowel 26 and thus is adapted to clean or remove the rear face and edge of such member from any plastic or cementitious material or other matter tending to accumulate thereon. The contact surfaces between the cleanser 32, disc trowel 26, trowel supporting body 27 and plate 33 are lubricated and kept clean by lubricant supplying means 36 and 37. Such means include suitable lubricant containers 38 and 39, respectively, for holding lubricant under pressure of feeders 40 and 41 actuated by springs 42 and 43, respectively. From the container 38 the lubricant flows through line 44 in the cleanser 32 through lateral ways 45 to oil grooves 46 and 47 on the confronting surfaces of the trowel 26 and the cleanser 32. Lubricant also passes from line 44 to an oil groove or grooves 48 on the confronting surfaces between the trowel supporting member 27 and the cleanser 32. Lubricant from the chamber 39 passes through the line 50 to an oil groove or grooves 51 on the confronting surfaces between the body 27 and cleanser 32 and thence through way 52 to oil groove 53 on the confronting surfaces between the plate 33 and cleanser 32.

Preferably in order to facilitate the disassembly of the apparatus or to permit rollers of different sizes to be used as the forming and spreading means, the roller 20 is made in three sections, of which 54 is a central or main section of the roller 20 and 55 indicates one of the two end sections provided. This permits the length of the roller to be readily varied. The end section 120

55 is indicated as split and held together and to the shaft 28 by a bolt 55^a.

As an additional method and means of insuring a finished edge being formed on the plaster board, it is desirable to provide means for continually maintaining the rollers 20 and 21 clean. For this purpose a wiper 57 is provisioned to continually bear against the rear side of the roll 20. This wiper 10 may be of any desired form, preferably maintained slightly moist.

As the plaster board is formed by rolls 20 and 21, there is a slight tendency of the roller 20 to pick up the formed board to 15 carry the same therewith. This action operates to prevent the desired even edge being formed. In order to overcome this tendency, a bar 58 is provided contacting slightly with the roller 20, in the position 20 indicated in Fig. 4, where it will arrest and prevent the plaster board from being carried or picked up by the roll 20.

It will be apparent that by the use of the herein described apparatus the fibrous sheets 25 11 and 12 are fed to the rollers 20 and 21 of equal length therewith. The trowel 26 is continually driven as the plaster board is formed smoothing off the edges of the board and forming thereby a finished appearing 30 board. The trimmer 26 and rolls 20 are continually cleaned to prevent accumulation of hard material thereon, which hinders formation of the finished edge. The formed 35 plaster board is caused to pass directly away from the forming and spreading means and thus leaves the trowel and finished edges unaffected until the plaster board is dried and used.

While the method and apparatus for 40 forming plaster board herein described is well suited for accomplishing the purposes of this invention, it is to be understood that various modifications in the details of the method and apparatus may be made without 45 departing from the spirit of the invention, and the invention is not therefore limited to the specific form described, but is of the scope set forth in the appended claims.

I claim:

50 1. A method of forming plaster board which comprises continually trowelling the edges of the plaster board as the same is formed by incorporation of plastic or cementitious material between fibrous covering sheets.

55 2. The method of forming plaster board which includes continually trimming fibrous covering sheets to the size of the desired finished plaster board, continually supplying plastic or cementitious material therebetween, and continually trowelling the edges of the formed board at the point of incorporation of the plastic or cementitious material.

60 3. The method of forming plaster board,

which includes continually passing fibrous covering sheets to forming and spreading rollers, continually supplying plastic or cementitious material between the sheets at the rollers, the sheets being so supplied that as the boards are formed they are of equal length with the rollers, and continually trowelling the edges of the board as formed. 70

4. The method of forming plaster board, 75 which comprises continually passing sheets of fibrous covering material between spreading or forming rollers, continually supplying plastic or cementitious material between the sheets at the rollers, continually trowelling the edges of the board as formed to 80 form a plaster board with a finished edge, and restraining the plaster board as formed from being picked up by the forming or spreading rollers.

5. The method of forming plaster board comprising continually advancing fibrous covering sheets to spaced rollers, continually feeding cementitious or plastic material between the sheets as passed between such rollers, the sheets advanced to the rollers being of equal length therewith as they pass therebetween, and continually trowelling the edges of the plaster board as formed. 85

6. An apparatus for forming plaster board comprising fibrous covering material supply means, forming and spreading means, means for advancing the fibrous covering material to the forming and spreading means and conveying the same therefrom, means for supplying plastic or cementitious material between the fibrous covering materials at the forming and spreading means, and trowels positioned to engage the edges of the 90 plaster board as formed, and means for continually actuating said trowels. 100

7. An apparatus for forming plaster board comprising means for continually advancing fibrous material, means for supplying plastic material between said fibrous material as the same is advanced, means for trimming the fibrous material to predetermined size prior to addition of plastic material, trowels disposed in engagement with the edges of the plaster board as formed, and means for moving the trowels to form finished edges on the 110 board. 115

8. An apparatus for forming plaster board comprising fibrous material supply means, plastic material supply means, forming and spreading rollers, advancing means for feeding the fibrous material to said rollers and for conveying away the produced board, trowelling means at the ends of said rollers operative to produce finished edges on the board, and means engageable with the board as formed operative to restrain said rollers picking up the board. 120

9. An apparatus for forming plaster board, comprising fibrous material supply 130

means, means for supplying plastic material between supplied fibrous material, forming and spreading rollers, and trowels mounted on the rollers for finishing the edges as 5 formed.

10. An apparatus for forming plaster board comprising means for continually advancing fibrous material, means for interposing plastic material between spaced sheets 10 of the fibrous material, rollers operative to spread said plastic material, trowels at the ends of the rollers, means for moving the trowels to finish the edges of the pro-

duced board, and means for continually cleansing the trowels.

15

11. An apparatus for forming plaster board comprising forming and spreading rollers, means for advancing fibrous material to said forming and spreading rollers, means for supplying plastic material at the rollers, means carried by the rollers for producing finished edges, trowels at the ends of the rollers, and means for cleaning the trowels.

20

Signed at Los Angeles, California this 19 day of February, 1925.

JOHN SCHUMACHER.
